UNITED STATES PATENT OFFICE.

WILBUR F. BURNS, OF BRIDGEPORT, CONNECTICUT, ASSIGNOR TO THE BASSICK CO., OF BRIDGEPORT, CONNECTICUT, A CORPORATION OF CONNECTICUT.

FURNITURE-LEG MOUNT.

1,278,432.

Specification of Letters Patent. Patented Sept. 10, 1918.

Application filed December 5, 1917. Serial No. 205,690.

To all whom it may concern:

Be it known that I, WILBUR F. BURNS, a citizen of the United States, residing at the city of Bridgeport, county of Fairfield, State of Connecticut, have invented certain new and useful Improvements in Furniture-Leg Mounts; and I do declare the following to be a full, clear, and exact description of the invention, such as will enable others skilled in the art to which it appertains to make and use the same.

This invention relates to certain new and useful improvements in a leg mount for furniture legs, and more particularly to legs constructed of angle iron, the main drawback to the universal use of angle iron legs for household furniture residing in the angular edges and their inability to facilely glide over the floor without injury to the floor or to the article of furniture.

Attachments have heretofore been devised for the lower ends of angle iron legs but their unsightly appearance has had its detrimental effects with manufacturing concerns as well as the purchasing public even though they otherwise perform their function and office in a very efficient manner.

The principal object of this invention is found in the construction of a leg mount that will be efficient in operation and thoroughly pleasing to the esthetic emotions by blending with the design of the angle iron construction.

Further, the invention resides in the salient structural features hereinafter described and claimed, reference being had to the accompanying drawing wherein—

Figure 1 is an inside view of a fragmentary portion of an angle iron leg, depicting the present invention applied thereto;

Fig. 2 is a vertical section thereof on line 2—2 of Fig. 1;

Fig. 3 is a horizontal section taken on line 3—3 of Fig. 1.

Fig. 4 is a front elevation of the improved attachment; and

Fig. 5 illustrates the invention in slightly modified form, having a caster support.

Referring more in detail to the drawing, the numeral 1 designates a leg of angle iron construction frequently employed on metal furniture.

The leg mount or glider attachment com-

prises a triangular bottom plate 2 having upturned marginal flanges or vertical walls 3 each of rectangular design and meeting the companion wall in overlapping relation at the included corner of the triangular bottom whereby said walls 3 constitute a continuous but angular wall. The walls 3 are designed to embrace the outer angular faces of the leg in flat contact to represent a band encircling the leg and present a neat finish about the same without any projecting parts.

Numeral 4 indicates the spring clamping wall or member that is turned up from the inner edge of the bottom plate and bent backwardly between the inner faces of the leg, said clamping member being of triangular design to present inwardly converging edges 5 for wedging against said inner faces of the angular leg. The free apex 6 is turned or rolled outwardly to provide ample room for the insertion of a prying tool for withdrawing the clamping member and also to provide a tongue which may be struck a blow for increasing the clamping action of said member against the sides of the leg by causing the former to conform more closely to the interior design of the leg.

When used as a glider attachment the bottom plate has depressed therefrom a spherical or rounded bearing 7 which supports the bottom plate off the floor and permits easy sliding movement of the furniture thereover.

As depicted in Fig. 5, the glider bearing may be dispensed with and a caster 8 substituted, the pintle 9 of which is passed upwardly through registering openings in the bottom and back walls, the latter being extended vertically in this embodiment rather than being rolled back like in Fig. 2, said vertical part having its upper end turned outwardly at right angles to provide a top wall 10 in which the upper end of the pintle is secured.

In either form, the back wall is turned up from the inner edge of the bottom and forced inwardly into frictional contact with both inside walls of the leg. The outside appearance is neat and finished with practically no material modification of the external design and contour of the leg, the edge flanges representing a band extending about

the leg. The attachment may be securely fastened to the leg and is readily removable by springing the resilient clamping wall out from engagement with the inside of the 5 leg.

What is claimed is:

1. A leg mount for angle iron legs, comprising a triangular bottom plate having on its two front edges upturned substantially 10 rectangular walls that meet at the included angle; and a clamping member turned upwardly from the back edge at a forward inclination to engage the inner faces of the leg at points directly opposite the walls.
- 15 2. A leg mount for angle iron legs, comprising a triangular bottom plate having on its two front edges upturned walls for engaging the outer faces of a leg, and a clamping plate turned upwardly from the back 20 edge directly at a forward inclination between the angularly related inner faces of the leg, the edges of the clamping plate converging forwardly and upwardly for engaging both inner faces of the leg whereby 25 said clamping plate may be wedged down-

wardly into closer frictional contact with the inner faces of the leg.

3. A leg mount for angle iron legs, comprising a triangular bottom plate having on its two front edges upturned walls for 30 engaging the outer faces of a leg, and a clamping plate turned upwardly from the back edge directly at a forward inclination between the angularly related inner faces of the leg, the edges of the clamping plate converging upwardly and forwardly for 35 engaging both inner faces of the leg whereby said clamping plate may be wedged downwardly into closer frictional contact with the inner faces of the leg, the apex of the 40 clamping plate being turned backwardly to provide a part which may be struck to wedge said clamping plate tighter between the inner faces of the leg.

In testimony whereof I affix my signature. 45

WILBUR F. BURNS.
